WATER-HEATER.

1,324,071.

Specification of Letters Patent.

Patented Dec. 9, 1919.

Application filed September 4, 1918. Serial No. 252,507.

To all whom it may concern:

Be it known that I, GERHARDT F. SCHWARTZ, a citizen of the United States, and a resident of St. Louis, Missouri, have 5 invented certain new and useful Improvements in Water-Heaters, of which the following is a specification.

My present invention has for its object to improve water heaters for the purpose of 10 securing a greater efficiency, simplicity of construction and elimination of copper coils or other internal water-heating devices or channels, and also of obtaining a very efficient and sensitive device for regulating 15 the heat through a thermostatic appliance. For this purpose, I have devised certain improvements, a specific embodiment of which is illustrated in the accompanying drawings.

Figure 1 is a central vertical section of 20 such heater;

Fig. 2 is a horizontal section on line 2—2 of Fig. 1;

Fig. 3 a top plan view of a condensation pan forming part of this apparatus;

Fig. 4 a vertical section on line 4—4 of Fig. 3; and

Fig. 5 a top plan view of the second combustion burner and its water jacket substantially on line 5—5 of Fig. 1.

Water from a suitable source of supply is admitted through the pipe 10 extending downwardly through a bushing 11, fitted into the top or cover 12 of the tank proper, having a cylindrical metallic wall 13 pref- 30 erably surrounded by a jacket 14 of asbestos or other suitable heat retaining material; that is to say, a poor conductor of heat.

Into the lower end of the pipe 10 extends the upper end of a thermostatic tube 15 of 40 copper containing a porcelain rod, said tube passing through a bushing 16 in the annular bottom 17 of the tank, and having its lower end connected with a thermostat 18, the detail construction of which forms the subject-matter of another application. It will suffice to say here that the fuel gas enters the thermostat at 19, and that this thermo- 45 stat contains a valve controlling the passage of said gas to the pipes 20 and 21, the latter

50 having a pilot light, while the former extends into the air tube or mixing tube 22, open to the surrounding air at the bottom, and leading to a double combustion burner of a character set forth in other applications 55 for patents previously filed by me, for instance, Serial No. 58,927, filed October 30th,

1915. The said burner is composed of a primary burner 23, having annular or slit like substantially horizontal outlets, by which the flame is directed against a surrounding vertical wall 24, and above said primary burner is located the secondary burner plate 25 provided with openings 26, and extended at its periphery to form the top wall of a water jacket 27 surrounding 60 said wall 24. The jacket is provided with a partition 28, and at one side of said partition a pipe 29 communicating with the water jacket 27 extends upwardly to connect with a union 29' and with a vertical pipe 29'' 65 reaching from the bottom 17 of the tank to a point near the top of said tank, through which also extends a pipe 30 for conducting the hot water to the place of use, said pipe 30 being preferably in line with the pipe 29''. 70

75 Connections may be made to a water back of well-known construction by means of a tube or nipple 31 located about half way between the top and bottom of the tank, and another nipple 32 located near the bottom 80 of the tank. The nipple 32 has two connections, one of them indicated at 33 leads to the jacket 27; the other, indicated at 34 (and preferably made in two portions connected by a union 34') leads to a nipple 35 85 at the lower portion of the tank. The burner with its jacket is substantially of the same construction as in Figs. 4 and 5 of my application Serial No. 58,927 above referred to, but instead of having the connections 29, 90 33 extending upwardly at opposite sides of the partition 28, one of the said connections, to wit, the pipe 33, is arranged horizontally and enters the vertical wall of the jacket 27.

95 Into the central opening of the tank bottom 17 is fitted a flue 36 preferably corrugated as shown, and this flue together with the adjacent edge of the tank bottom is fitted into an annular channel 37 of a condensation pan, which in addition to said 100 annular channel comprises a central pan or dish 38 spaced from said channel so as to provide an annular opening 39, the two parts of the pan being suitably connected as by lugs 40. Into the central portion 38 of 105 the condensation pan is fitted another flue 41 preferably also corrugated, said flue being of considerably smaller diameter than the flue 36, so that an annular heating chamber 42 will be formed between them. 110 The condensation pan closes the bottom of the central flue 41, which latter extends up-

wardly through the top 12 of the tank, and is open for the discharge of the combustion products. The flue 36 does not extend to the top of the tank, but say to about one-third of its height only, and is provided with a top plate 43 to close the heating chamber 42. Immediately below the said top plate 43, an opening 44 is provided in the central flue 41, and in the upper portion of the flue 41 above the top plate 43, is arranged a spiral baffle 45 which if desired, may be corrugated as shown at the upper portion, while the lower portion is shown plain or smooth surfaced. The baffle may be either entirely corrugated or entirely smooth.

The heater rests on suitable legs 46, and is provided with a base 47 surrounding the burner, and said base is preferably provided with two doors, one of them indicated at 48 to facilitate access to the burner, and the other 49 provided with a notch at one of its edges or corners for the passage of the pipe 33.

It will be understood that the combustion at the primary burner will heat the water in the jacket 27, which water is supplied through the pipe 33. The water thus heated passes from the jacket 27 into the heater tank, through the pipe 29. The water supplied to the jacket 27 through the pipe 33 comes partly from the water back, and partly from the lower portion of the tank through the nipple 35, or all from the lower portion of the tank if no water back connections are made.

The secondary combustion takes place above the burner plate 25, and the combustion products are projected against the bottom 17 of the tank, and against the condensation pan, and are compelled to pass through the annular channel 39 between the central portion 38 and the annular channel 37 of the condensation pan. The combustion gases thus reach the heating chamber 42, the outer wall 36 of which forms a large surface in contact with the water at the lower portion of the tank, that is to say, in contact with the coldest part of the water. The combustion gases rise in the chamber 42 along the said wall 36, and pass through the opening 44 into the central flue 41. In the upper portion of the flue 41, which upper portion is in contact with the water contained in the tank, the combustion gases are retarded by the spiral baffle 45, so as to cause them to give up most of their remaining heat to the water contained in the tank. Any matter condensed from the combustion gases within the chamber 42 will flow down partly along the inner surface of the flue 36, into the annular chamber 37 of the condensation pan and partly along the outer surface of the flue 41 into the central portion 38 of said pan. Any matter condensed

within the flue 41 will flow along the inner surface of said flue into the central portion 38 of the condensation pan.

The condensation pan may be held against the lower edges of the flues 36, 41 by a post or leg 50 interposed loosely between the second combustion burner top 25 and said pan, so that the pan can be removed readily for cleaning and also to give access to the flues when desired.

The burner or water-heating member located beneath the tank, can be detached readily for cleaning or other purposes, by simply unscrewing the two unions 29', 34'.

While I have illustrated and described a satisfactory embodiment of my invention, it is obvious that changes may be made therein within the spirit and scope thereof, as defined in the appended claims.

I claim:

1. A water heater comprising a water tank, a one-way flue extending within said tank from top to bottom, a condensation pan at the lower end of said flue, another flue arranged within the tank and surrounding the lower portion of the first-named flue, the annular space between the two flues being out of communication with the water space of the tank, but communicating with the inner flue at a point slightly below the top of the outer flue, and means for supplying a heating medium to said annular space at the bottom thereof.

2. A water heater comprising a water tank, a flue extending within said tank from top to bottom, another flue arranged within the tank and surrounding the lower portion of the first-named flue, the annular space between the two flues being out of communication with the water space of the tank, but communicating with the inner flue at a point slightly below the top of the outer flue, and a condensation pan fitted to the lower edges of said flues and provided between them with an opening for the admission of a heating medium to said annular space.

3. A water heater comprising a water tank, a flue extending within said tank from top to bottom, another flue arranged within the tank and surrounding the lower portion of the first-named flue, the annular space between the two flues being out of communication with the water space of the tank, but communicating with the inner flue at a point slightly below the top of the outer flue, a central dish into which extends the lower edge of the inner flue, an annular channel spaced from said dish and receiving the lower edge of the outer flue, and means for introducing a heating agent into the space between the said dish and said channel.

4. A water heater comprising a water tank, a flue extending uprightly through said tank, a condensation pan at the lower end of said flue, a burner disposed directly

beneath said condensation pan, the center of said pan being substantially in the vertical axis of said burner, and means for supplying a heating medium from said burner transversely to said flue above said condensation pan.

5. A water heater comprising a water tank, a one-way flue extending within said tank from top to bottom, a condensation pan 10 at the lower end of said flue, another flue arranged within the tank and surrounding the lower portion of the first-named flue, said outer flue being corrugated, the space between the two flues being out of communication 15 with the water space of the tank, but communicating with the inner flue, and means for causing a heating medium to pass first through said space between the flues and then through the inner flue.

20 6. A water heater comprising a water tank, a one-way flue extending within said tank from top to bottom, a condensation pan at the lower end of said flue, another flue arranged within the tank and surrounding the 25 lower portion of the first-named flue, the annular space between the two flues being out of communication with the water space of the tank, but communicating with the inner flue at a point slightly below the top of the 30 outer flue, and means for causing a heating medium to pass through said space and through the inner flue.

7. A water heater comprising a water tank, a one-way flue extending within said 35 tank from top to bottom, another flue arranged within the tank and surrounding the lower portion of the first-named flue, the annular space between the two flues being out 40 of communication with the water space of the tank, but communicating with the inner flue at a point slightly below the top of the outer flue, a condensation pan at the bottom of both flues, and means for causing a heating medium to pass through said annular 45 space and through the inner flue.

8. A water heater comprising a water tank, a flue extending within the tank at the lower portion thereof, a one-way flue of smaller widths extending from the top of the 50 tank into the first-named flue, the space between the two flues being out of communication with the water space of the tank, but communicating with said one-way flue, and means for causing a heating medium to pass 55 through the space between the flues and through said one-way flue.

9. A water heater comprising a water tank, a flue extending within the tank at the lower portion thereof, a flue of smaller width 60 extending from the top of the tank into the first-named flue, the space between the two flues being out of communication with the water space of the tank, but communicating with the inner flue, a condensation pan at the 65 lower ends of both flues, and means for caus-

ing a heating medium to pass through the space between the flues and through the inner flue.

10. A water heater comprising a water tank, a flue extending uprightly through 70 said tank, means for supplying water to said tank, heating means below said flue, a single annular water channel surrounding said heating means laterally, a lateral water inlet pipe extending to said channel and 75 connected to said tank, and a vertical outlet pipe adjacent said lateral inlet pipe and extending to the upper part of said tank.

11. A water heater comprising a water tank, a flue extending uprightly through 80 said tank, means for supplying water to said tank, heating means below said flue, an annular water channel surrounding said heating means laterally, a water inlet pipe extending to said channel and connected to the 85 lower part of the tank, and an outlet pipe extending from said channel upwardly through said tank exteriorly of said flue and having its outlet end disposed in the upper part of said tank.

90 12. A water heater comprising a water tank, a flue extending uprightly through said tank, means for supplying water to said tank, heating means below said flue, an annular water channel surrounding said heating means laterally, a lateral inlet pipe extending to said channel, and connected to the lower part of the tank, and a vertical outlet pipe extending from said channel upwardly through said tank and having its 100 outlet end disposed in the upper part of said tank.

95 13. A water heater comprising a water tank, a flue extending uprightly through said tank, heating means below said flue, 105 said flue being subject primarily to the rising heat from said heating means, a water channel surrounding said heating means laterally and being subject primarily to the lateral heat from said heating means, water 110 inlet means for said channel, a water outlet means extending from said channel upwardly through said tank exteriorly of said flue and having its outlet end disposed in the upper part of said tank.

115 14. A water heater comprising a water tank, a flue extending uprightly through said tank, a cold water inlet pipe extending downwardly through said tank and having its outlet end disposed in the lower part of 120 said tank, a water channel surrounding said heating means and subject to heat therefrom, water inlet means for said channel, and warm water outlet means extending from said channel upwardly through said tank 125 exteriorly of said flue and having its outlet end disposed in the upper part of said tank.

15. A water heater comprising a water tank, a flue extending uprightly through said tank, heating means disposed below said 130

- flue and comprising a primary burner, a top plate over said burner in close proximity thereto provided with openings for secondary combustion surrounding said burner at 5 a level above the burner top, said plate immediately above the burner being unperforated, a downwardly extending flange on said top plate entirely inclosing said primary burner laterally, and an annular water jacket surrounding said flange laterally, 10 water inlet means for said water jacket, and water outlet means extending from said channel upwardly through said tank exteriorly of said flue and having its outlet end disposed in the upper part of said tank. 15
16. A water heater comprising a water tank, a one-way flue extending within said tank from top to bottom, a condensation pan at the lower end of said flue, another 20 flue arranged within the tank and surrounding the lower portion of the first named flue, the annular space between the two flues being out of communication with the water space of the tank, but communicating with 25 the inner flue at a point slightly below the top of the outer flue, means for supplying a heating medium to said annular space at the bottom thereof and a spiral baffle disposed in said inner flue and having its lower end 30 adjacent the point of communication between said annular space and said inner flue.
17. A water heater comprising a water tank, a one-way flue extending within said tank from top to bottom, a condensation pan 35 at the lower end of said flue, another flue arranged within the tank and surrounding the lower portion of the first named flue, the annular space between the two flues being out of communication with the water space
- of the tank, but communicating with the inner flue at a point slightly below the top of the outer flue, means for supplying a heating medium to said annular space at the bottom thereof and a corrugated spiral baffle disposed in said inner flue and having its 45 lower end adjacent the point of communication between said annular space and said inner flue. 40
18. A water heater comprising a water tank, a heating flue extending through said tank, a burner located below said tank, a condensation pan engaging the lower end of said flue, and a removable support interposed between said pan and the top of the burner. 50
19. A water heater comprising a water tank, a heating flue extending through said tank, a burner located below said tank, a condensation pan engaging the lower end of said flue, and a removable support interposed 60 between said pan and the top of the burner. 60
20. A water heater comprising a tank, a flue extending through said tank, a removable condensation pan engaging the lower end of said flue, a water heating member located beneath said tank, a removable support interposed between said pan and said member and two unions for connecting said member with the tank to enable the said member to be detached upon unscrewing said 70 unions. 65

In testimony that I claim the foregoing as my invention, I have signed my name in presence of two subscribing witnesses.

GERHARDT F. SCHWARTZ.
